UNITED STATES PATENT OFFICE.

WILLIAM F. McCOLLUM, OF LOS ANGELES, CALIFORNIA, ASSIGNOR OF ONE-HALF TO
GRACE McCOLLUM, OF LOS ANGELES, CALIFORNIA.

CONCRETE-WALL FORM.

Application filed March 22, 1923. Serial No. 626,773.

To all whom it may concern:

Be it known that I, WILLIAM F. McCOLLUM, a citizen of the United States, residing at Los Angeles, in the county of Los Angeles and State of California, have invented new and useful Improvements in Concrete-Wall Forms, of which the following is a specification.

My present invention is a system of concrete construction and apparatus for use therein, it being a special object of this invention to provide simple means and improved methods for the construction of hollow walls, and especially hollow walls having corners; and in the employment of the means and methods referred to, I prefer to utilize a comparatively dry mixture of the usual or any desired concrete materials, and to build successive tiers or courses of a wall therefrom in situ.

It is an object of this invention to provide a system of forms which shall permit of the spacing apart of the respective shells constituting a hollow wall, and to provide also a specific and improved method of so reinforcing walls of the character referred to that the respective shells need not come into actual contact at any point, although securely connected together.

It is a further object of this invention to employ reinforcing elements which may serve also as rails or supports for the sliding parts of a collapsible core form; and it is a further object to provide specific core forms, operating or guiding means therefore, end gates, spacing means, holding means and other details of concrete apparatus, the parts referred to being adapted effectively to cooperate in a manner hereinafter described.

It is a further object of this invention to provide both corner forms and straight wall forms suitable for use in the production of hollow reinforced walls of any desired length and in such manner that, the respective corners being preferably laid first, one tier or course of blocks may be rapidly superimposed upon another in a manner which shall facilitate the insertion of reinforcement and the breaking of all joints, it being possible to proceed by the method referred to with such rapidity that the resulting structure may be substantially monolithic.

Other objects of my invention will appear

from the following description of preferred embodiments thereof and the appended claims; but I desire especially to emphasize the fact that, while the principles of my invention are suitable for use in the construction of hollow walls or channel walls of any desired type, certain features being applicable even in the construction of solid walls, I prefer to apply the mentioned principles in the construction of walls which may be compared with those of a thermos bottle in that an inner shell is so effectively spaced from an outer shell that the transfer of heat, sound or moisture therethrough is effectively prevented.

One preferred type of apparatus suitable for use in the practice of my invention, is shown in the accompanying drawings, in which—

Fig. 1 is a plan view showing a set of forms adapted to be associated in the production of a corner of a hollow wall.

Fig. 2 is an elevational view taken in the direction indicated by the arrow 2 in Fig. 1.

Figs. 3 and 4 are detail perspective views showing elements used in the connecting of outside vertical form elements with a collapsible core of the character shown in Fig. 1.

Fig. 5 is a plan view showing a set of interconnected form elements suitable for use in the formation of a block or section of straight wall.

Fig. 6 is a detail view showing a preferred method of connecting and supporting an outside vertical form element with the corresponding element of a core or other mold used in the formation of a channel or air space between an inner and an outer shell.

Fig. 7 is a vertical section substantially on the line 7—7 of Fig. 6.

Fig. 8 is a horizontal section substantially on the line 8—8 of Fig. 7.

Fig. 9 is a detail perspective view showing a preferred means for moving and guiding the vertical elements constituting a core form such as I prefer to employ in the organization shown in Fig. 5.

Figs. 10, and 11 are respectively a plan view and a side elevation of a connecting and supporting strap of the type which I prefer to employ in the relationship best indicated in Figs. 7 and 8.

Fig. 12 is a vertical sectional view show-

ing how a corner form of the character shown in Fig. 1 may be supported from a tier or course of wall previously formed, and how a core form of my preferred construction 5 may be provided with means to effect a relative movement of parts.

Fig. 13 is a perspective view showing how I prefer to employ reinforcing elements in the construction of a hollow or channel wall, 10 the Z-shaped reinforcing elements shown in this figure being intended to provide supporting rails for the core form which is shown in cross section in Fig. 12.

Fig. 14 is a perspective view of a preferred 15 form of end gate which I may use in connection with either my corner forms or my straight forms, the outside of this end gate being shown in vertical elevation in Fig. 2.

Fig. 15 is a detail view on the line 15—15 of Fig. 16 and showing how my end gate may cooperate with the elements of a core form and may also aid in the positioning and supporting of a reinforcing element by 20 which the inner and outer shells of a hollow or channel wall may be connected.

Fig. 16 may be regarded as a vertical section on the line 16—16 of Fig. 15.

Referring first to the details of my preferred 30 type of corner forms shown best in Figs. 1, 2, 3 and 4, it will be understood that the vertical elements of this set of forms are respectively the core elements 1 and 2, which are secured together by pin 35 and slot connections comprising slotted straps 3 and stud-carrying straps 4, which may be respectively riveted to angle irons 5 and 6, which are secured in turn to the vertical plates 7 and 8, which may be of sheet 40 metal, and which are respectively provided at the bottom with angle irons 9 and 10, disposed in the relative position best shown in Fig. 2.

In order to properly space and support 45 the outside vertical form elements comprising the plates 12 and 13, provided at the top with angle irons 14 and 15, and at the bottom with corresponding angle irons 16 and 17, any suitable construction may be 50 employed, but I prefer to employ, adjacent the top of the core forms, and secured thereto by means of the projecting ears 18, the laterally extending bolts 19, shown as provided with the nuts 20 and with the sleeves 55 21, the latter being optionally secured by means such as the pins 22, and the bolts 19 being preferably provided with constrictions 23 at the outer ends thereof, the mentioned constrictions being adapted to extend 60 through key-hole slots 24 in ears 25 upon the angle irons 14, 15, at the top of the respective outside vertical form elements 12, 13. Washers 26 may optionally be interposed between the ends of the sleeves 21 and 65 the ears 18, it being understood that the

sleeves referred to serve not only as spacing and strengthening means but also as handles by which the associated parts may be conveniently lifted, when desired, as a unit. At the bottom of the forms described I may 70 employ supporting and spacing connections such as the straps 27, best shown in Figs. 6-10 inclusive, these straps being preferably provided at one end with key-hole slots 28, and at the other end with a threaded extension 29, adapted to carry the wing nuts 30, and optionally secured by means such as the chains 31^a, which may be connected with any adjacent part, such as the angle irons 16, 17. Slots 31, 32 being provided in the 75 core plates 7 and 8, and in the outside vertical form elements 12, 13 respectively, it will be understood that the slots 28 may be engaged by the studs 31^b upon the respective 80 core plates, and that the wing nuts 30 may thereafter be employed to space the outside form elements therefrom in such manner as to render the vertical surfaces of all the mentioned form elements substantially or exactly parallel and vertical; and when the 85 bottom of an outside vertical form element has been secured in the manner referred to, a latch element 33, shown as pivoted upon a bracket 34 secured to the ear 25, or any 90 equivalent means, may be employed to secure the bolts 19 within the key-hole slots 24 at the top of the respective forms.

In beginning the construction of a wall of a building by means of the forms herein described, I prefer to place the corner blocks 100 in position first; and as soon as the parts already described have been assembled in the manner indicated, the ends of the form being closed in any suitable way, I may proceed to place any suitable concrete mixture 105 within the spaces between the outside surfaces of the core elements and the outside vertical form elements; but I prefer to employ, at the ends of both my corner forms and my straight forms, end gates of the specific construction best shown in Figs. 2, 110 13, 14 and 15, from which it will be understood that I may provide notched fins 35 upon the inner side of plates 36, the edges of which may be reinforced by the horizontally extending angle irons 37 and the vertically extending angle irons 38, the latter being adapted to support the horizontal angle irons or straps 39 to which I may 115 secure any suitable fastening means such as the latches 40, shown as pivoted at 41 and adapted to engage the studs 42, the use of stops 43 being optional. It will be observed that the vertical fins 35 are shown as provided with notches 44, and these notches I prefer to employ as means for supporting reinforcing elements such as the U-bars 45, it being understood that these U-bars may be inserted during the filling of 120 my molds with concrete and they may serve 125 130

as a permanent connecting means between the inner and outer shells of a wall formed in the manner described.

As best shown in Fig. 14, the vertical fins 35 may serve not only as a means for strengthening my end gates and as a means for temporarily supporting the reinforcing elements referred to, but also as an extension of the plates 7 and 8, by which the air space 10 or channel between the shells of a wall of my preferred construction is defined, it being understood that after a corner has been formed, preferably by the use of a comparatively dry concrete mixture, the core 15 elements above described may be withdrawn, when collapsed, by a vertical movement, and that the end gate may be moved laterally in order to permit of the use of a straight form or forms, at the ends of the corner block or section formed in the manner described.

Any suitable means may be employed to produce a relative movement between the vertical plates 7 and 8, to diminish the distance between these plates when my core forms are to be withdrawn; but I find it advantageous to employ for this purpose the elements 46 and 47, respectively pivoted to the angle irons 5 and 6, it being understood 25 that corresponding pairs of pivoted elements 48 and 49 are correspondingly secured to the lower angle irons 9 and 10, and that a handle 50 provided with a vertical extension 51 is rigidly secured to the respective pivoted 30 elements 46 and 48, in such manner that a lateral movement of this handle in one direction tends to move the plates 7 and 8 toward one another in a cornerwise or diagonal direction, corresponding to the direction of the 35 respective slots in the elements 3, also connected therewith, it being understood that pin and slot connections such as those referred to above are provided not only at the top but at the bottom of the plates 7 and 8 and connected with the angle irons 9 and 10.

After corner blocks have been suitably formed in situ in the manner above described, or in any other preferred manner, I may assemble at the ends of the lateral extensions thereof straight forms of any suitable design; but I prefer to employ in this connection forms which are in some respects closely similar to the corner forms already described. As best shown in Figs. 5 and 9, 50 I may embody in my straight forms the core elements 1^a and 1^b, secured together by the pin and slot connecting elements 3^a and 4^a, and connected with the angle irons 5^a and 6^a which carry and strengthen the vertical plates 7^a and 8^a of a collapsible core, it being understood that pin and slot connections of the character referred to are employed not only at the top but at the bottom of this core, as best shown in Fig. 9, and that any suitable operating means may be associated 55

therewith. One suitable operating means is shown in the figures referred to as comprising pivoted elements 52 and 53, respectively secured to the horizontal angle irons 5^a and 6^a, and to the corresponding elements 9^a and 10^a at the bottoms of the respective plates, the pivoted elements 52 and 53 being shown in turn as pivotally connected with T-shaped levers 54, the movement of which by means such as the arms 55, rigidly connected with a rock shaft 56, provided with a handle 57, is adapted to produce a relative movement between the vertical plates 7^a and 8^a, in order to permit a form to be withdrawn after a block shall have been completed. 60

It should be understood that, in the completion of a first course in situ, an end gate such as that described above may be used in connection with not only the corner forms but also with the straight forms described, 65 and that when a first course or tier of blocks, preferably provided with reinforcement in the manner indicated, shall have been laid, successive courses may be similarly laid thereon substantially in the manner described, or in any other suitable way. 70

In the laying of successive courses, I find it advantageous to provide means by which, the forms having been removed from the blocks of such a first course, the blocks of a next course may be supported therefrom, and I prefer to proceed in such a way as to break joints between the blocks of successive courses, and with sufficient rapidity to permit of the bonding of the successive courses into a substantially monolithic structure. In order suitably to support each course subsequently to the first course from a course of blocks previously laid, any suitable means 75 may be employed but I prefer to employ in this connection reinforcing elements, which may be laid upon the respective tops of the blocks comprising a lower course and extending in such a direction as suitably to support the elements of my collapsible core forms during the relative movement thereof. For example, in preparation for the formation of a second tier comprising corner blocks to be laid upon previously formed blocks such as are shown in Fig. 13, I may employ means such as the Z-bars 59, whose central straight portion is preferably arranged to extend in the direction of the slots in the elements 3, and substantially in the 80 same vertical plane therewith, it being understood that, for the supporting of the cores used in the formation of my straight blocks, mere fragments of scrap iron, or the like, may optionally be employed to support the pin and slot connecting elements 3^a, 4^a, 85 of which I may employ any desired number. 90

It is an important merit of my described organization of form elements that, by merely varying the length of the connecting elements such as are shown in Figs. 4 and 11, 95

or by providing a plurality of constrictions 23 in the former and a plurality of slots 28 in the latter, I may adapt the major elements of my device to be associated with 5 end gates of varying width in the production of walls differing in outside diameter.

Although I have herein described one preferred means for the formation of corner blocks and one preferred means for the formation of straight blocks, my means referred to being adapted either to conjoint or separate use, various elements of my invention might be independently used, and various modifications might be made therein 15 without departing from the spirit and scope of my invention as the same is indicated above and in the following claims.

What I claim is:

1. In a means for concrete wall construction, an end gate provided with means for supporting reinforcing elements from said end gate.
2. In apparatus for the construction of walls, a collapsible core, and means for securing and spacing outside vertical form elements therefrom, said securing and spacing means comprising a strap adapted to extend through slots in said outside form elements, one element having a stud to engage in a slot in one end of the strap and there being a screw and nut on the other end of the strap.
3. In apparatus for the construction of walls, a collapsible core, and means for securing and spacing outside vertical form elements therefrom, said securing and spacing means comprising a strap adapted to be secured at one end by a slot and stud connection and at the other end by a screw and nut.
4. In apparatus for the construction of concrete walls and comprising vertical form elements, means for spacing and supporting said vertical form elements from a corresponding tier of wall previously formed, 45 said spacing and supporting means comprising a strap adapted to be inserted through slots in said form elements and to rest upon said tier of wall previously formed, one element having a stud to engage in a slot in one end of the strap and there being a screw and nut on the other end of the strap.
5. In apparatus for the construction of concrete walls and comprising vertical form elements, means for spacing and supporting

said vertical form elements from a corresponding tier of wall previously formed, 55 said spacing and supporting means comprising a bolt adjustably pivoted at one end and adapted to extend through a key-hole slot at the other end.

6. In apparatus for the construction of hollow concrete walls, a plurality of pairs of vertical corner elements secured one 60 within another, and means for causing one pair of such corner elements to move corner-wise toward another pair thereof.

7. In apparatus for the construction of hollow concrete walls, a plurality of pairs of vertical corner elements secured one 65 within another, and means for causing one pair of such corner elements to move corner-wise toward another pair thereof, said means comprising slotted elements disposed in the direction of such movement.

8. In apparatus for the construction of hollow concrete walls, a plurality of pairs of vertical corner elements secured one 70 within another, and means for causing one pair of such corner elements to move corner-wise toward another pair thereof, said means comprising slotted elements disposed in the direction of such movement, and adapted to be supported by diagonal reinforcement.

9. In apparatus for constructing hollow concrete walls, and end gate provided with 85 means for supporting reinforcing elements therefrom.

10. In apparatus for constructing hollow concrete walls, an end gate provided with vertical fins adapted to cooperate with core 90 elements in providing an air space, and provided with means for supporting reinforcement.

11. In apparatus for constructing hollow concrete walls, an end gate provided with 95 vertically movable latching elements.

12. In apparatus for constructing hollow concrete walls, means comprising bolts extending through sleeves and provided with 100 constrictions suitable for engagement with key-hole slots for adapting identical outside vertical form elements provided with such slots to be used alternatively with various end gates in the production of walls differing in outside diameter.

In testimony whereof I have signed my name to this specification.

WILLIAM F. McCOLLUM.
